Wesley G. Carr
ATTORNEY

UNITED STATES PATENT OFFICE.

KARL TAMELE, OF BERLIN-WILMERSDORF, GERMANY, ASSIGNOR TO WESTINGHOUSE ELECTRIC & MANUFACTURING COMPANY, A CORPORATION OF PENNSYLVANIA.

FURNACE.

Application filed December 2, 1926, Serial No. 152,153, and in Germany December 3, 1925.

My invention relates to furnaces and more particularly to cooling means for bright-annealing furnaces.

An object of my invention is to provide a simple and efficient furnace.

Another object of my invention is to provide means for quickly cooling the interior of the furnace at the end of the heat-treating period.

Other objects of my invention will be apparent from the disclosure.

A drawback of electrically heated, bright-annealing furnaces, in which a protective gas is employed, is that the cooling of the furnace and the material therein at the end of the heat-treating period requires a long time, during which the material cannot be removed, because, if removed, it would become oxidized. My invention ensures the quick cooling of the furnace and its contents without exposing such contents to the outside atmosphere.

In each of the forms of my invention herein described, a furnace, having a material-receiving chamber adapted to be heated by suitable means, such as electric heating elements, is provided. The material-receiving chamber has a hollow member, provided with heat-conducting walls, extending through it. While the furnace is being heated, the passageway provided by the hollow member is closed by heat-insulating closure means; when the furnace has been sufficiently heated, the closure means are removed and air is permitted to circulate through the passageway, thereby effecting a rapid cooling of the chamber and the material therein.

In the drawing,

Fig. 1 is a sectional view of a furnace embodying my invention,

Fig. 2 is a sectional view of a modification of my invention.

Referring to the drawing for a more detailed description of my invention, a furnace 10 comprises a lower member 11, preferably of bowl shape, having a cover member 12, the members 11 and 12 being constructed of refractory insulating material.

Mounted on the cover member 12, is an auxiliary cover member 13, the lower rim 14

of which extends into an oil seal 15 that is secured, in any suitable manner, to the lower member 11, thus providing an oil seal for the furnace. The cover member 13 is spaced from the cover member 12 by means of spacers 16 that may be secured to either of the cover members, but, in the present instance are secured to the cover member 13.

Suitable heating means is provided and, in the form of my invention shown in Fig. 1, such heating means comprises electric heating elements 18 that are positioned in the material-receiving chamber 19 of the furnace and are secured to the walls of the lower member 11.

A preferably metallic pipe, or cylindrical casing, 20, extends through the center of the furnace.

The ends of the pipe 20 are open to the outside atmosphere.

The pipe 20 is vertically disposed and is removably positioned within openings 21, 22 and 23 in the bottom wall of the member 11, the cover member 12 and the cover member 13, respectively. The pipe 20 has a flange 24 at its upper end to rest on an annular member 26 that, in turn, is supported by the auxiliary cover member 13.

A cylindrical member 28 is secured to the bottom wall of the member 11 and is positioned in the opening 21 of that wall. The cylindrical member 28 surrounds the lower end of the pipe 20 and may be spaced from the walls thereof.

The cylindrical member 28 extends below the bottom wall of the member 11 and is immersed in an annular oil seal 30 which is preferably secured to the bottom wall of the member 11 by suitable means, such as the brackets 32. As is clearly shown in Fig. 1, the pipe 20 is also immersed in the annular oil seal 30. The annular oil seal 30, therefore, prevents any communication between the chamber 19 and the interior of the pipe 20.

Means are provided for closing the ends of the pipe 20 to prevent communication between the interior of the pipe and the outside atmosphere. In the form of my invention shown in Fig. 1, such means comprises a lower

stopper or closure member 34 and an upper stopper or closure member 35. The closure members 34 and 35 are preferably rigidly connected by means of a rod 36 that is secured hereto in any suitable manner, as by means of screw threads (not shown).

The upper stopper 35 preferably has a flange portion 38 that is adapted to rest against the flange 24 of the pipe 20, for more effectively closing the upper end of the pipe. The pipe 20 may be of such length that the lower stopper member will also rest against the inner wall of the annular oil seal 30, if desired. The upper closure member 35 is provided with an eye member 39 so that the closure members 24 and 35 may be removed, when desired, by means of a crane or other lifting device, the hook of the crane being attached to the eye member 39. In charging the furnace, the closure members 34 and 35, the pipe 20 and the cover members 12 and 13 are removed and the material 40 is placed in the proper position in the furnace. The cover members 12 and 13, the pipe 20 and the closure members 34 and 35 are then replaced. The heating elements, which are connected to a suitable source of electrical energy (not shown), are then energized and the material 40 is heated to the proper temperature which is maintained for such period of time as is necessary for the heat-treating operation.

At the end of the heat-treating period, the energy is cut off from the heating elements 18, and the closure members 34 and 35 are then removed to permit cold air to circulate through the circular opening of the coil seal 30 and the pipe 20. The air circulation is aided by the transmission of heat, through the metallic wall of the pipe 20 from the chamber 19, to the air passing through the pipe, thus creating a vertical draft. In this way, the chamber 19, and, therefore, the material 40 will be rapidly cooled.

A pit 41 may be formed in the furnace foundation 42, into which the pipe 20 opens. This pit may be connected to means for producing a forced draft through the pipe 20.

In the form of my invention shown in Fig. 2, the furnace is essentially the same as the furnace shown in Fig. 1, and comprises a lower member 42, a cover member 43, both made of refractory insulating material, and an auxiliary cover member 44 that is spaced from the cover member 43 by means of spacers 45. The rim of the cover member 44 is immersed in an oil seal 46.

The lower member 42 is of bowl shape, thus providing a chamber 48 therein that constitutes the material-receiving chamber. Within the chamber 48 are provided electric heating elements 49 that are secured to the walls of the lower member 42 by any suitable means.

A pipe 50 extends vertically through the chamber 48, the bottom wall of the member 42 and the cover members 43 and 44 and is

rigidly secured to the bottom wall of the member 42. An inverted flange member 52 is positioned within the upper end of the pipe 50 and is secured thereto by any means, as by welding, to provide a liquid-tight joint. Within the annular recess 54, thus formed, oil is preferably placed and, immersed in this oil, is an annular flange 55 that is integral with the cover member 44. This forms a seal between the pipe 50 and the cover member 44. The member 52 may have an opening therein to permit circulation of air therethrough during the cooling period. A flange 57 may be formed at the lower end of the pipe 50.

Stoppers or closure members 58 and 59 are positioned, respectively, at the upper and lower ends of the pipe and are connected by a rod 60. The closure member 59 is preferably provided with a flange 61 which is adapted to bear against the flange 57 in order to make a better closure.

Underneath the pipe 50, a pit 62 is formed in the floor or foundation 63 on which the furnace rests which is open to the outside atmosphere. At the bottom of the closure member 59, an eye member 64 is preferably formed.

In operating the furnace, material 65 is placed therein in a manner similar to the placing of material in the furnace shown in Fig. 1, previously described, and the heating elements 49 are energized to heat the material to the proper temperature. At the end of the heat-treating period, the closure members 58 and 59 are removed by suitable means engaging the eye member 64. The closure members will, of course, be drawn downwardly into the pit 62. The air is thus permitted to enter the pipe 50 to cool the pipe and thereby cool the furnace. Forced draft may be utilized to aid in the cooling, if desired. Since the cooling pipes in the furnaces described, occupy considerable space, the space to be filled with protective gas is reduced. This renders the furnaces especially useful for annealing annular objects.

Although I have shown and described, for purposes of illustration, only two embodiments of my invention, the invention may, of course, be embodied in other forms without departing from the spirit and scope thereof, as set forth in the appended claims.

I claim as my invention:

1. In a furnace, in combination, a casing provided with a material-receiving chamber, electric heating means in said chamber, a metallic pipe mounted in said casing and extending vertically through the center of said chamber, a pair of connected removable stoppers fitting in said pipe for heat-insulating the interior thereof from the outside atmosphere, whereby the pipe will act as a manually controlled cooling means.

2. In a furance, in combination, a casing provided with a material-receiving chamber, electric heating means in said chamber, a metallic pipe mounted in said casing and extending vertically through the center of said chamber, a hermetically sealed cover for said chamber, a pair of connected removable plugs fitting in said pipe for heat-insulating the interior thereof from the outside atmos-phere, and a compartment adapted to communicate with one end of said pipe upon removal of said plugs, whereby the pipe will act as a manually-controlled cooling means.
- In testimony whereof, I have hereunto subscribed my name this 9th day of November, 1926.

KARL TAMELE.
